(57) **CLAIM**

The ornamental design for an eductor nozzle and manifold unit assembly, as shown and described.

DESCRIPTION

FIG. 1 is a top perspective view of an eductor nozzle of an eductor nozzle and manifold unit assembly shown in a disassembled state;

FIG. 2 is a bottom perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a top perspective view of a manifold of an eductor nozzle and manifold unit assembly shown in a disassembled state;

FIG. 10 is a bottom perspective view thereof;

FIG. 11 is a front elevation view thereof;

FIG. 12 is a rear elevation view thereof;

FIG. 13 is a right elevation view thereof;

FIG. 14 is a left elevation view thereof;

FIG. 15 is a top plan view thereof;

FIG. 16 is a bottom plan view thereof;

FIG. 17 is a top perspective view of an eductor nozzle and manifold unit assembly;

FIG. 18 is a bottom perspective view thereof;

FIG. 19 is a front elevation view thereof;

FIG. 20 is a rear elevation view thereof;

FIG. 21 is a right elevation view thereof;

FIG. 22 is a left elevation view thereof;

FIG. 23 is a top plan view thereof;

FIG. 24 is a bottom plan view thereof; and,

FIG. 25 is an exploded view thereof.
